(57) **CLAIM**

The ornamental design for tray for sterilization and freeze-drying of vials, as shown and described.

DESCRIPTION

FIG. 1 is a front elevational view of a tray for sterilization and freeze-drying of vials showing my new design;

FIG. 2 is a rear elevational view thereof;

FIG. 3 is a perspective view thereof;

FIG. 4 is an enlarged front view of the part defined by the line 4-4 and 4'-4' of FIG. 1 thereof;

FIG. 5 is an enlarged rear elevational view of the part defined by the line 4-4 and 4'-4' of FIG. 1 thereof;

FIG. 6 is a cross-sectional view taken along the line 6-6 in FIG. 4 thereof;

FIG. 7 is a cross-sectional view taken along the line 7-7 in FIG. 4 thereof;

FIG. 8 is an enlarged perspective view of the front side of the part defined by the line 4-4 and 4'-4' of FIG. 1 thereof; and
FIG. 9 is an enlarged perspective view on the rear side of the part defined by the line 4-4 and 4'-4' of FIG. 1 thereof.

FIG. 10 is a referential sectional view taken along the line 7-7 in FIG. 4 showing the state of use thereof.

FIG. 11 is a top plan view thereof;

FIG. 12 is a bottom plan view thereof;

FIG. 13 is a right side view thereof; and,

FIG. 14 is a left side view thereof.

The broken lines in the drawing depict parts of the tray for sterilization and freeze-drying of vials that form no part of the claimed design.

1 Claim, 14 Drawing Sheets
